UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

APPARATUS FOR MINING COAL.

1,378,830.

Specification of Letters Patent.

Patented May 17, 1921.

Original application filed April 7, 1915, Serial No. 19,746. Divided and this application filed August 23, 1919, Serial No. 319,449. Renewed March 3, 1921. Serial No. 449,502.

To all whom it may concern:

Be it known that I, NILS D. LEVIN, a citizen of the United States, residing at Columbus, in the county of Franklin and State of Ohio, have invented certain new and useful Improvements in Apparatus for Mining Coal, of which the following is a specification, reference being had therein to the accompanying drawing.

10 This invention relates to apparatus for mining coal, and particularly to apparatus of the class by which coal is dislodged from its native bed and loaded into conveniently positioned cars for transportation from the mine.

15 The especial object of this invention is to provide apparatus of the class described having improved conveying mechanisms whereby the coal is received as it is dislodged from its native bed and is deposited in suitably positioned cars for transportation from the mine.

20 In my co-pending application, Serial No. 19,746, filed April 7th, 1915, of which this present application is a division, is disclosed an apparatus of the class described comprising mechanism adapted to be moved while operating either inward to make the sumping cut or in either direction along straight lines parallel with the face of the coal to dislodge the material from its native bed and load it into cars conveniently positioned upon the mine tracks for transportation from the mine. Included in said mechanisms is a system of conveyers adapted to convenient adjustment whereby connection may be maintained between the dislodging mechanism and the pit car during the various phases of operation of the machine.

- Referring to the construction in detail, the base frame comprises a bottom plate 1 adapted to slide over the floor of the mine. This plate 1 is attached to the depending flanges 2 of the bed frame casting 3 upon which are mounted the other parts of the machine. Supported by the depending brackets 3^a from the under side of the bed frame casting, and adapted to limited longitudinal movement thereon, is a cutter frame 4. The cutter frame comprises a bottom plate 5 on which are placed a chain guide bar 6 and stiffening bars 7 and 8. Upon these bars are placed the top plates 9 and 10, and all of the parts are securely riveted together, as shown. Guide strips 11 are secured along the edges of the plates to engage the links of the chain 12 to prevent their accidental removal from the guide ways thus formed.
- 20 The chain 12 can be of standard construction and it need not be described in detail. It is provided with cutters 12^a. The outer surface of the guide bar 6 is protected by a renewable wearing strip 13 over which the chain slides. The top plate 9 is cut away at 14 to form a slot the edges of which engage the aforesaid bracket 3^a, which carries an adjusting screw 15 in threaded engagement with the nut casting 16 attached to the bottom plate 5. By means of the screw 15 it is possible to move the cutter frame for the adjustment of the tension of the cutter chain 12 in the manner common to chain cutter mining machines. The cutter frame is extended laterally and rearwardly along the right hand side of the machine for a purpose which will presently appear, and on account of the unbalanced strains due to this extension, there is preferably provided a second adjusting screw 17, carried by a casting 18 secured to the bottom plate 1 and engaging the rear edge of the cutter frame to maintain the frame in proper alignment with the base frame 3. Clamping bolts 19 and 20 extending through slots in the cutter frame enter threaded apertures in supporting blocks 21 secured to the bottom plate 1 to assist in holding the parts in their proper working relation.

- Mounted upon the base frame casting 3 is an electric motor 22 having an armature 23 mounted in suitable bearings 24 and 25. Secured to the shaft of this armature is a spur pinion 26 engaging with a spur gear 27 mounted upon a shaft 28 journaled in bearings on the base frame casting. The spur gear 27 is connected through a friction disk safety device 29 with a bevel pinion 30 which meshes with the master bevel gear 31. Any overload transmitted to the bevel pinion 30 from the master gear 31 will cause a slippage of the friction disks of the safety device 29 and prevent the overloading of the motor. The master gear 31 is fixed on a vertical shaft 32 which is journaled in the
- bearings 33 of the base frame casting and in the bearing 34 of an auxiliary frame secured thereto. Mounted upon the lower end of the vertical shaft 32 is a sprocket wheel 35 by which the cutter chain 12 is driven. Suitable clutch mechanism is interposed between the sprocket wheel 35 and the vertical shaft 32 by which they may be connected or disconnected as the conditions of operation may require. As concerns this clutch there can be variation, but for purposes of illustration I have shown the shaft 32 as provided with an apertured flange 32^a. The sprocket wheel 35 is similarly apertured and in a conical recess of the wheel is a ring which carries vertical pins 35^a adapted to extend through both sets of apertures. When the pins are in the position shown the sprocket wheel is connected to the shaft, but by lifting the pins they can be disengaged from the flange 32^a, thus breaking the power connection to the sprocket wheel 35.
- Formed on the hub of the bevel gear 31 is a worm 36 which engages the worm wheel 37 keyed to the shaft 38 extending across the machine and supported in the bearings 39, 40 and 41 attached to the base frame casting 3. Mounted upon this shaft 38 is a cable winding drum 42 upon which may be wound the cable 43 by which the machine may be moved and guided about the working place as will be later explained. Upon one side of this drum 42 is formed the driven member 44 of a friction clutch of the well known Weston multiple disk type, the driving member 45 of which is keyed to the shaft 38. Attached to the clutch member 44 is an inward extending flange 46 provided with a central screw threaded aperture engaging similar threads on the hub of a spur gear 47. The gear 47 is freely mounted upon the shaft 38 in such a manner that the rotation of the gear 47 relative to the clutch member 44, in one direction will actuate the clutch to drive the drum and in the other direction will release it. Convenient means for the manipulation of the spur gear 47 is provided in the pinion 48 attached to the shaft 49 journaled in suitable bearings of the machine frame, and having its end squared to fit a convenient wrench for manual rotation.
- A second friction clutch 50, similar to the clutch above described, is mounted on the shaft 38 and upon the driven member of this is formed a spur pinion 51 which engages a spur gear 52 keyed to the shaft 53. A spur gear wheel 54 is provided for the manipulation of the clutch 50, and this gear is controlled by the spur pinion 55 attached to the shaft 56 adapted to be controlled with a hand wrench in the same manner as the first described clutch. To the shaft 53 is fixed a pinion 57 engaging the gear wheel 58 to drive the feed shaft 59 and with it the feed drum 60. A feed cable 61 is attached to

the drum 60 to be wound thereon to feed the machine to its work as will be later explained.

Positioned at suitable points about the machine are guide sheaves 62, 63, 64, 65, and 66 by which the feed cable 61 may be led in any desired direction for the proper manipulation of the machine, as will be fully set forth, and a swiveled sheave 67 10 is provided adjacent to the drum 42 by which the cable 43 may be guided in either direction.

A convenient reverse switch 68 is provided by which the direction of rotation of the armature 23 may be controlled. Starting and stopping of the motor is effected by the starting box 69 having a handle 70 located convenient to the hand of the operator.

The conveyer is of the endless chain and scraper type and is carried by a self-contained structure having a forward horizontal part lying in a recess of the cutter frame and an inclined rearward portion extending along the right hand side of the motor frame 20 to a point in the rear of the feed and guiding mechanism to discharge the coal into any receptacle placed conveniently to receive it.

The forward horizontal portion of the structure comprises two parallel side rails 71 which have secured to them the angle bars 72. To these angle bars is attached the plate 73 which forms the bottom of the conveyer trough. Formed in the side rails 30 71 are notches adapted to engage the square-headed studs 74 fixed to the bottom plate 5 to prevent longitudinal movement of the conveyer structure. Cover plates 75, bolted to the upper frame, engage the upper edges 40 of these side rails to hold them in place. The chains of the conveyer are indicated by 79 and are provided with rollers 78. Because of the difficulty of properly lubricating the bearings of a revolving shaft continually exposed to dust in the limited space available at the forward end of the cutter frame, the foot shaft 76 is fixed to the side rails 71 and upon the surface of this shaft 45 are formed two circular flanges 77 upon the periphery of which the rollers 78 of the conveyer chains 79 travel. The carrier strand of the conveyer chains 79 and the cross bars 80 travel on the plate 73 to push the coal along the trough, and the return 50 strand travels over the bottom plate 5 to a point 81 near the foot shaft 76 where the plate is cut away to afford additional clearance.

The inclined rear portion of the conveyer structure comprises two side plates 82 and 83, attached at their forward ends to the side rails 71. To these side plates are fixed the angles 84 which support the trough plate 73, and the angles 85 which support the return strands of the chains 79. Angles 60

86 secured to the side plates 82 and 83 protect the chains from contact with the coal in the trough. Channel bars 87 and 88, secured to the main frame 3 of the machine, and vertical angle bars 89 secured to these 70 channels form a structure which supports the rear end of the conveyer. Secured to the side plates 82 and 83 near their rear end, are adjustable journal boxes 90 of the type commonly used in conveyer practice 75 to afford means for tensioning the conveyer chains, and in these is journaled the head shaft 91 having suitable sprocket wheels 92 and the chain 93 with the sprocket wheel 94 fixed upon the transverse shaft 95 journaled 80 in bearings 96 of the machine frame and driven by the bevel gears 97 and 98 from the vertical shaft 32 to drive the conveyer. A removable side plate 99 is provided for use at the forward end of the conveyer after 85 the completion of the sumping cut. Secured to the back of this plate 99 are attachment lugs 100 adapted to be inserted in apertures 101 provided for their reception in the plates and bars of the cutter frame. 90 The use of this removable plate will appear in the description of the operation of the machine as hereinafter set forth.

As concerns the breaking down mechanism, there can be wide variation, but I 95 prefer a mechanism which consists of a mechanically operated pick of any suitable type, such as is commonly used for undercutting coal. Although anyone of a number of well known mechanisms might be used, 100 I have shown, for purposes of illustration, a pneumatically actuated pick mechanism of a well known manufacture, having a cylinder 102 within which is a piston carrying a tool 103 adapted to reciprocatory motion. 105 Compressed air is supplied from any convenient source through a suitable air hose 104 and controlled by a conveniently placed valve 105. Formed on the sides of the cylinder 102 at about its center of weight are 110 trunnions 106 adapted to be supported in suitable bearings of a yoke 107 which is pivoted for rotation in a horizontal plane, in the hub 108 of the goose neck bracket 109. Convenient handles 110, attached to 115 the rearward end of the cylinder 102, afford means to direct the blows of the pick against any desired point in the coal face.

Formed at the other end of the bracket 109 is a hub 111 in which are mounted the 120 ball bearings 112, 113, and 114, the inner races of which engage the pivot post 115 fixed in the top and bottom plates 116 and 117 of the horizontally oscillatable arm 118, affording a support for the bracket 109 and 125 the parts carried thereby. The ball bearings, being sufficiently massive, afford an abutment for the thrust of the pick against the coal face as transmitted through the trunnions 106, the yoke 107 and the bracket 130

109. Hinged to the bracket 109 is a latch 119 adapted to engage with notches in the segmental plate 121 attached to the arm 118 concentric with the pivot post 115 to prevent the rotation of the bracket about the pivot. A cord 122 attached to the latch 119 and leading around the guide sheave 123 to the hand of the operator at the handle 110, affords means for disengaging the latch when such rotation is desirable.

110. The arm 118 is built up of the top and bottom plates 116 and 117 and the channel bars 124, and is pivotally attached to the supporting platform 125 by the pivot bolt

115. 126. The platform 125 comprises the plate 127 supported from the motor frame 22 by two sections of channel bar 128 bolted to the motor frame and riveted to the plate 127, and of an angle bar 129 fixed to the forward 20 edge of the plate 127 and extending above the conveyer and along the right hand side of the machine and supported by angle bars 89 and 89^a of the machine frame. Spaced apertures in the angle bar 129 are adapted to 25 receive the lugs 131 of the stop block 132 by which the oscillation of the arm 118 may be limited.

130. In mines adapted for the room and pillar system of mining, entries or passages, along which the coal is transported, are excavated in the coal body and from these entries open the rooms in which the principal mining operations are conducted. Tracks are laid along the entries for the passage of the cars 35 in which the coal is hauled, and from these tracks extend branches into the rooms. For reasons which it is not necessary to recite at this time, these branch tracks are usually laid along one side of the room, and as the 40 mining operations extend across the end of the room much of the coal must be carried a considerable distance to be loaded into cars standing upon such tracks. On this account I have found it advisable to use an auxiliary 45 conveyer, extending along the working face in such relation thereto that it will receive the coal discharged from the machine conveyer, as it advanced across the face, and deliver the same to an auxiliary loading conveyer which in turn delivers it to the cars.

150. As illustrated in Fig. 13, the auxiliary face conveyer comprises a trough 133, of similar construction to that used in the inclined portion of the conveyer upon the 55 mining machine, which is supported at either end on pedestals 134 and 135, each provided with a sole plate 136 and 137 respectively, adapted to slide over the floor of the mine in any direction, to facilitate 60 placing the conveyer in working relation with the mining machine. Along the trough 133 travel two endless strands of the chains 138 connected together at intervals by cross bar scrapers 139 by which the coal is propelled along the trough. A head shaft 140

and a foot shaft 141 are provided at the ends of the trough to guide the chains 138 in the manner common to conveyer practice. A driving shaft 142, journaled in suitable bearings supported by the trough structure, carries sprocket wheels 143 which engage the return strands of the chains 138 to drive them, and idler sprockets 144, suitably mounted, hold the chains 138 in working engagement with the sprocket wheels 143. 70 The drive shaft 142 is connected through the sprocket wheels 145, the chain 146 and the sprocket wheel 147 with the motor 148, mounted in the pedestal 134. 75

135. A loading conveyer which is suitable to the purposes of this invention is illustrated in Fig. 15 but it is to be borne in mind that these devices are subject to wide variation without departing from the spirit of my invention. As illustrated in Fig. 15 this 80 conveyer comprises two sections of trough 149 and 150, the former of which extends in an upward inclined direction while the latter extends in an approximately horizontal direction above the cars 151 standing 85 on the rails 152 of the mine track. These trough sections are connected together by a horizontal hinge 153 to admit of a certain amount of vertical adjustment of the delivery end of the trough 150. Secured to the 90 trough 150 are forward extending arms 154 connected through the links 155 with the cross yoke 156 which is in threaded engagement with the adjusting screw 157 by which the said adjustment may be effected. This 95 loading conveyer is supported on a structure comprising a hopper casting 168, adapted to slide over the floor of the mine, and a steel framework 179, built up of structural shapes 100 suitably connected together and to the hopper casting according to the practice of structural steel construction. An axle 180 and wheels 181, adapted to travel on the rails 152 of the mine track, are provided to support the weight of the rear portion of 105 the framework 179 and to facilitate the positioning of the conveyer for service. The hopper casting 168 is shaped to form the forward portion of the conveyer trough, and is provided with suitable bearings in which 110 is journaled the foot shaft 182. At the rearward extremity of the horizontal section 150 are fixed journal boxes 183 of the ordinary adjustable type commonly used in conveyer practice to regulate the tension of the 115 conveyer chains 184. The conveyer chains 184 pass around the sprocket wheels of the head and foot shafts in the manner common to scraper conveyers, and are connected together at intervals by the cross bar scrapers 120 185 which slide over the bottom plates of the troughs 149 and 150 to propel the coal there-through. Mounted in suitable bearings of the structural frame 179 is a shaft 186 which 125 is so positioned that the line of the return 130

- strand of the conveyer chain 184 is approximately tangential to the periphery of the sprocket wheels 187 mounted thereon. These sprocket wheels 187 engage the chains 184 to drive them, a sufficient amount of slack being provided to insure engagement with the teeth of the wheels. The shaft 186 is driven through suitable gearing from the motor 179 mounted upon the framework 179.
- 5 When operated according to the perferred method of use, the machine is brought into the mine room and placed at one side, as for example near the right hand rib adjacent the working face with the forward end of the cutter frame as close up into the corner as is convenient, as illustrated in Fig. 16. The feed cable 61 is then drawn out from the drum 60, passes around the guide sheave 62 and secured to a suitable anchor jack 188 adjacent the working face of the coal. The guide cable 43 is then drawn out from the drum 42, passed around the swiveled sheave 67 and the guide sheave 65 and attached to a suitable anchor 189 adjacent the right hand rib. The auxiliary face conveyer 133 is then adjusted in position to receive material delivered by the machine conveyer, and the loading conveyer 149 is adjusted in position to receive material from the face conveyer and deliver it to a car 151 suitably positioned upon the mine track 152. When the machine is started, and the feed cable 61 wound upon the drum 60, the machine will be caused to move forward to make the sumping, or entering, cut. By the manipulation of the friction clutches 44 and 50 the drums 42 and 60 may be caused to wind their respective cables 43 and 61, to hold them against unwinding or to allow them to freely unwind as the operator may desire. By such manipulation of the clutches the ropes 43 and 61 will be controlled to bring the machine into the position shown in Fig. 17. As soon as the cutter frame, with the forward end of the machine conveyer, is sufficiently advanced beneath the coal, compressed air will be admitted to the breaking down mechanism, causing the reciprocation of the pick tool 103. The operator may move the pick mechanism upon its support to direct the stroke of the pick tool 103 against any desired points in the coal face to break out fragments therefrom upon the conveyer to be removed thereby.
- 45 While the machine is operating as illustrated in Figs. 16 and 17 the right hand end of the face conveyer 133 may be conveniently adjusted to maintain its operative relation with the machine conveyer to receive the coal delivered therefrom without disturbing the relation of the left hand end of the face conveyer with the loading conveyer 149. After the completion of the sumping cut the face conveyer 133 may be
- 50 and the loading conveyer 149 advanced to maintain operative relation with the face conveyer as illustrated in Fig. 18.
- 55 After the machine has been drawn to the maximum distance into the coal, the jack 188 is removed to a point adjacent the left hand rib and a feed cable 61 is connected thereto as illustrated in Fig. 18. The clutches 44 and 50 are then manipulated to feed the machine across the face of the room in the manner well understood by those skilled in the art. As the machine advances the pick mechanism breaks down the coal and the conveyers carry it to the cars. The operation will thus be continued, as illustrated in Fig. 19, until the entire width of the room has been traversed. If now the feed drum 60 be held against rotation and the guide cable 42 be wound up, the rear end of the machine will be drawn toward the right, and the forward end of the cutter frame forced to the left to finish the cut as illustrated in Fig. 20.
- 60 The feed rope 61 will then be passed around the guide sheaves 63, 64, 65 and 66 to the anchor jack 189 positioned adjacent the coal face, and the guide rope 43 attached to the anchor jack 188 adjacent the left hand rib as illustrated in Fig. 21. The sumping operation is then repeated in substantially the same manner as that described at the right hand side of the room. After the sumping cut has been completed at the left hand side of the room, by the manipulation of the feeding and guiding clutches, the machine will be straightened up as illustrated in Fig. 22, the anchor jack 189 will then be set adjacent the right hand rib and the cutting operation may be continued from left to right as illustrated in Fig. 23. During the operation of the machine from left to right the manipulation of the face and loading conveyer is substantially similar to that when operating from right to left. While the machine is operating across the face of the room in either direction, there is formed a secondary coal face at an angle with the principal coal face and extending inwardly to the vertical plane of the inner end of the cutter frame. During such operation the pick mechanism 102 may be swung upon its support into any desired position to cause the engagement of the pick tool 103 with either the principal coal face or with the secondary coal face as may be desired for the most efficient breaking down of the coal.
- 65 When mining machines of the usual weight and dimensions are used, and it is desired to cut first in one direction and then in the other, it has been found expedient to reverse the cutter bits in the cutter chain and to reverse the direction of the cutter chain, to prevent the pick reaction from forcing the machine away from the coal face, and the devices here described

are adapted for operation in that manner. But experience with the machine embodying my invention as described, has demonstrated that the additional weight of the 5 breaking down and conveying mechanisms prevents the movement of the machine by such reaction and it is possible to cut in both directions without changing the bits or reversing the chain.

- 10 As soon as the sumping cut is completed in either side of the room the removable plate 99 is adjusted to confine the broken coal to the conveyer, and when the cut has been completed across the room this plate 15 will be again removed to be out of the way while sumping.

What I claim is—

1. An apparatus for mining coal comprising a horizontally extending kerf cutter 20 adapted to be moved either longitudinally or laterally to form a kerf at the base of a coal vein, means for breaking down the coal above said kerf, a conveyer in fixed relation with said kerf cutter adapted to receive and remove said coal as it is broken down, and an auxiliary conveyer extending longitudinally of the coal face adjustable relative thereto, and adapted to receive the 25 broken coal from said receiving conveyer.
2. An apparatus for mining coal comprising a horizontally extending kerf cutter adapted to be moved either longitudinally or laterally to form a kerf at the base of a coal 30 vein, means for breaking down the coal above said kerf, a conveyer in fixed relation with said kerf cutter adapted to receive and remove said coal as it is broken down, and an auxiliary conveyer supported upon the 35 mine floor and slidable thereon into position to receive the broken coal from said receiving conveyer.

3. An apparatus for mining coal comprising a horizontally extending kerf cutter adapted to be moved either longitudinally or laterally to form a kerf at the base of a coal vein, means for breaking down the coal above the kerf, a conveyer in fixed relation with said kerf cutter adapted to receive and remove said coal as it is broken down, and an auxiliary conveyer extending longitudinally of said coal face supported upon the mine floor and slidable thereon into position to receive the broken coal from the receiving conveyer.

4. An apparatus for mining coal comprising a horizontally extending kerf cutter adapted to be moved either longitudinally or laterally to form a kerf at the base of a coal vein, means for breaking down the coal 60 above the kerf, a conveyer in fixed relation with said kerf cutter adapted to receive and remove the coal as it is broken down, a loading conveyer arranged to deliver material into a suitably positioned car, and an auxiliary conveyer extending longitudinally

of the coal face and adjustable to maintain operative connection between said receiving conveyer and said loading conveyer to transfer said broken coal to said car.

5. An apparatus for mining coal comprising a horizontally extending kerf cutter adapted to be moved either longitudinally or laterally to form a kerf at the base of a coal vein, means for breaking down the coal above said kerf, a conveyer in fixed 70 relation with said kerf cutter adapted to receive and remove said coal as it is broken down, a loading conveyer arranged to deliver material into a suitably positioned car, and an auxiliary conveyer extending longitudinally 75 of the coal face supported upon the mine floor and slidable thereon to maintain operative connection between said receiving conveyer and said loading conveyer to transfer said broken coal to said car.

6. An apparatus for mining coal comprising a horizontally extending kerf cutter adapted to be moved either longitudinally or laterally to form a kerf at the base of a coal vein, means for breaking down the coal above the kerf, a conveyer in fixed 90 relation with said kerf cutter adapted to receive and remove said coal as it is broken down, a wheel supported loading conveyer adapted to be moved along the rails of a mine track 95 and to deliver material to a car suitably positioned upon said track, and an auxiliary conveyer extending longitudinally of the coal face and adjustable to maintain operative connection between said receiving conveyer and said loading conveyer to transfer 100 said broken coal to said car.

7. An apparatus for mining coal comprising a horizontally extending kerf cutter adapted to be moved either longitudinally or laterally to form a kerf at the base of a coal vein, means for breaking down the coal above the kerf, a conveyer in fixed relation with said kerf cutter adapted to receive and remove said coal as it is broken down, a wheel supported loading conveyer adapted 105 to be moved along the rails of a mine track and to deliver material to a car suitably positioned upon said track, and an auxiliary conveyer extending longitudinally of the coal face supported upon the mine floor and slidable thereon to maintain operative connection between said receiving conveyer and said loading conveyer to transfer said broken coal to said car.

8. An apparatus for mining coal comprising a horizontally extending kerf cutter adapted to be moved longitudinally inward to make a sumping cut and laterally across the face of the coal to form a kerf at the base of a vein, means for breaking down the coal above the kerf, a conveyer in fixed relation with said kerf cutter adapted to receive and remove said coal as it is broken down, and an auxiliary conveyer extending 115 longitudinally of the coal face adjustable 120 to receive and remove said coal as it is broken down, and an auxiliary conveyer extending longitudinally of the coal face adjustable 125 to receive and remove said coal as it is broken down, and an auxiliary conveyer extending longitudinally of the coal face adjustable 130

relative thereto to maintain operative connection with said receiving conveyer and receive the broken coal therefrom.

9. An apparatus for mining coal comprising a horizontally extending kerf cutter adapted to be moved longitudinally inward to make a sumping cut and laterally across the face of the coal to form a kerf at the base of the vein, means for breaking down the coal above the kerf, a conveyer having a receiving portion positioned within the bounding planes of said kerf cutter and adapted to receive and remove said coal as it is broken down, and an auxiliary conveyer extending longitudinally of the coal face and adjustable relative thereto to maintain operative connection with said receiving conveyer and receive broken coal therefrom.
10. An apparatus for mining coal comprising a horizontally extending kerf cutter adapted to be moved longitudinally inward

to make a sumping cut and laterally across the face of the coal to form a kerf at the base of the vein, means for breaking down the coal above the kerf, a conveyer having a receiving portion positioned within the bounding planes of said kerf cutter and adapted to receive and remove said coal as it is broken down, a loading conveyer arranged to deliver material into a suitably positioned car, and an auxiliary conveyer extending longitudinally of the coal face and adjustable relative thereto to maintain operative connection between said receiving conveyer and said loading conveyer to transfer said broken coal to said car.

In testimony whereof, I affix my signature, in presence of two witnesses.
